UNITED STATES PATENT OFFICE.

WILLIAM H. BUTLER, OF NEW YORK, N. Y., ASSIGNOR TO THE AMERICAN TOBACCO COMPANY, OF NEWARK, NEW JERSEY.

BOX OR CAN.

SPECIFICATION forming part of Letters Patent No. 635,953, dated October 31, 1899.

Application filed April 7, 1896. Serial No. 586,502. (No model.)

To all whom it may concern:

Be it known that I, WILLIAM H. BUTLER, a citizen of the United States, residing at New York, (Brooklyn,) county of Kings, and State 5 of New York, have invented certain new and useful Improvements in Boxes or Cans, fully described and represented in the following specification and the accompanying drawings, forming a part of the same.

10 The object of the present invention is to provide an improved cover construction for boxes and cans especially adapted for use in common circular sheet-metal boxes and cans now in general use for holding various articles, but which may be applied also to boxes and cans of other character and material.

The invention relates to that class of boxes or cans in which one member is provided with a slightly-inclined surface coacting with an 20 engaging surface on the other member, so that the engaging surface moves up the incline as the cover is forced onto the box or can, and the cover is thus held more firmly the farther on it is pressed, and the invention 25 includes an improved construction of boxes or cans employing this general principle, as fully described and claimed hereinafter.

In the accompanying drawings, forming a part of this specification, Figure 1 is a longitudinal section of a box embodying the invention in one of the preferred forms, and Figs. 30 2, 3, and 4 are similar partial views showing modified constructions.

In each of the views, A is the circular box 35 or can, and B the screw-cover, which may be made wholly or partially of sheet metal, as usual in such constructions. As shown in Fig. 1, the body A is provided at the top with an internal bead 1, formed by rolling over the 40 edge of the sheet metal forming the body, a wire being inserted or not, as preferred. The screw-cover B has a straight sheet-metal flange 2, overlapping and screwing onto the outside of the box by screw-threads 5, and a 45 thicker metal rim 3, having a depending flange 4, projecting inside the box, and the external surface of this flange 4 tapers inwardly slightly, so as to form a slight incline engaging the rib 1. By screwing down the cover 50 B, therefore, the rib 2, which forms the engaging surface coacting with the incline, will

move up the inclined flange 4 or toward that part which is of larger circumference, and thus lock the cover on the box more firmly as the cover is pressed down, while the flange 2 55 moves over the outside of the body A and supports the latter against the locking pressure. The same result may be secured by various constructions.

In Fig. 2 the body A is provided with an 60 internal inclined flange 6, formed by bending over the top of the sheet-metal body, and the screw-cover B is shown as formed of a single piece of sheet metal, having the outside straight flange 2 and inside flange 4 of the 65 same form as previously described in connection with Fig. 1.

In Fig. 3 is shown a construction similar to that shown in Fig. 1, except that the cover is formed throughout of sheet metal and the 70 body is provided with a pin or projection 7 and the cover with a slot or groove 8, extending circumferentially of the box and being inclined toward the bottom of the box at a slight angle, so that by rotating the cover 75 upon the box, and thus moving the slot 8 along the pin 7, the cover is pressed down, securing the same result as the screw-threads 5. It will be understood that the pin and slot 80 may be arranged as shown, with the pin on the box and the slot on the cover, or this arrangement may be reversed, and that this pin-and-slot connection may be made in any suitable manner, the pin being formed by striking up a part of the metal or inserting a pin, 85 as preferred, and the slot or groove being formed by cutting away or striking up the metal. Any other form of inclined or screw connection may be used.

In all the constructions thus far described 90 the inclines are inside the box. It may frequently be preferable, however, to form the incline external to the box, and one form of such box is shown in Fig. 4. In this construction the circular sheet-metal box A is 95 provided with a rib 9, similar to rib 1 of Figs. 1 and 3, except that it is formed by rolling the edges of the box outwardly instead of inwardly, and the sheet-metal cover B is provided with a straight internal flange 10, entering the box and corresponding to the external flange 2 of the constructions previously 100

described, and with an inclined external flange 11, corresponding to the internal inclined flange 4, the screw-threads 5 being inside the box.

5 It will be understood that other modifications of construction may be made in carrying out my invention and I am not to be limited to the exact form of any of the constructions shown.

10 What I claim is—

A circular box or can and cover, one of said members having a surface inclined in the direction of movement of the cover and the other member having an incline engaging

surface, and an inclined or screw connection 15 between the cover and box, whereby the rotation of the cover presses the cover onto the box, forces the engaging surface up the incline and locks the cover in place, substantially as described.

20 In testimony whereof I have hereunto set my hand in the presence of two subscribing witnesses.

WILLIAM H. BUTLER.
